UNITED STATES PATENT OFFICE

2,377,558

APPARATUS FOR REMOVING CORNERS

Bernard C. Johnson, Mundelein, Ill., assignor to
Houdaille-Hershey Corporation, Detroit, Mich.,
a corporation of Michigan

Original application December 12, 1940, Serial No.
369,722. Divided and this application May 1,
1944, Serial No. 533,545

2 Claims. (Cl. 78—60)

This invention relates to apparatus for forming rounded edges on metal articles to eliminate sharp edges in order that coating material will uniformly cover the articles.

Specifically the invention deals with apparatus for pressing the aperture mouths of sheet metal evaporator units to eliminate all sharp edges therefrom in order that the evaporator unit can be uniformly coated with protective film such as zinc.

This application is a division of my copending application entitled: "Method of making evaporators," U. S. Serial 369,722 filed December 12, 1940.

While the invention will be hereinafter specifically described in connection with sheet metal evaporator units, it should be understood that the apparatus of this invention is useful in removing sharp edges from the aperture mouths of metal articles in general.

Metal articles having sharp edges cannot be uniformly coated, since the coating film will be quite thin at these edges and, in numerous instances, the sharp edges will project through the film. In the manufacture of sheet metal evaporator units from inexpensive metal such as mild steel, it is necessary to thoroughly protect all exterior surfaces of the units with a protecting film. Such sheet metal evaporator units are usually galvanized or tinned, and it is very difficult to cover the sharp edges of the units with such a protective film inasmuch as the film will draw thin or break entirely at the edges of the article.

The present invention now provides apparatus for dressing the sharp edges and corners of a sheet metal evaporator unit to provide rounded contours thereon which are readily covered with a protective film. The dressing operations are performed by pressing the annular aperture mouths of the sheet metal unit. A die press is used to round off the sharp aperture mouths. These dressing operations are preferably effected prior to the bending of the unit into its final shape and while the same is still in a flat condition.

It is, then, an object of the invention to prepare the aperture mouths of sheet metal articles for coating by dressing these mouths to form a rounded contour thereon.

A further object of the invention is to provide apparatus for working the metal around the aperture mouths in sheet metal articles to eliminate sharp corners or angles therefrom.

A further object of the invention is to provide

a die press for acting on the apertures of sheet metal articles to round out the aperture mouths and eliminate sharp corners thereon.

A specific object of the invention is to provide a die press with an enveloping sleeve for pinching metal adjacent an aperture in a metal article to squeeze the metal around the aperture to a rounded contour.

Other and further objects of the invention will be apparent to those skilled in the art from the following detailed description of the annexed sheet of drawings which, by way of preferred examples, illustrate two embodiments of the invention. On the drawing:

15 Figure 1 is an enlarged vertical cross-sectional view taken through one form of die for rounding the mouth of an aperture in a sheet metal article.

20 Figure 2 is a view similar to Figure 1 but illustrating the die in fully closed position and showing the manner in which the sheet metal is pressed to provide a rounded contour for the aperture.

25 Figure 3 is a view similar to Figure 1 but illustrating a modified form of die for rounding the aperture mouth.

Figure 4 is a plan view of an apertured metal sheet illustrating a rounded aperture mouth formed in accordance with this invention.

30 Figure 5 is a cross-sectional view taken along the line V—V of Figure 4 and illustrating the uniform protecting film covering the sheet metal.

Figure 6 is a view similar to Figure 5 but illustrating the defective protecting film formed when 35 the aperture mouths are sharp.

As shown on the drawing:
In Figures 1 and 2 the reference numeral 10 designates generally a metal article composed of metal sheets 11 and 12 secured together along 40 contiguous faces thereof by means of a bond such as a weld 13. The article 10 has a circular aperture 14 through both sheets 11 and 12. The aperture 14 has sharp mouths 15, 15 on each sheet 11 and 12. The article 10 is mounted on die 16 with the aperture 14 receiving the leading end of the die. This leading end of the die has a quarter-round bevel or groove 17. A top die 18 having a similar leading end with a ground 45 ed groove 19 cooperates with the die 16. The dies 16 and 18 are telescoped by sleeves 20 and 21 respectively which have rounded leading ends 22.

The leading ends 22 of the sleeves press into the faces of the sheets 11 and 12 to flow the metal into the aperture 14. As the dies close, the grooves 17 and 19 form a semi-cylindrical pocket

which receives the metal pressed from the faces of the sheets by the sleeves 20 and 21 to form a rounded periphery 23 for the aperture 14. The metal pressed by the leading ends 22 of the sleeves together with the metal pressed from the sharp corners 15, 15 will completely fill the die cavities as shown in Figure 2.

Alternatively, as shown in Figure 3, the sleeves 20 and 21 may be omitted from the dies 16 and 18. The quarter-round grooves 17 and 19 of the dies will dress the sharp corners 15, 15 of the aperture 14 sufficiently to form a rounded contour, although this rounded contour may not be as smooth as that obtained with the use of the sleeve.

As shown in Figures 4 and 5, the finished unit 10 with the rounded hole 14 can be galvanized to form the protective film 24 thereon. This protective film 24 will flow through the aperture 14 and be uniformly deposited thereon as at 25. If, on the other hand, as shown in Figure 6, the corners 15, 15 are allowed to remain around the aperture mouth 14, the film 24 will not uniformly flow through the aperture and will draw thin or rupture as at 26.

From the above descriptions it will be understood that the invention provides apparatus for the elimination of sharp corners from apertures through sheet metal articles in order that coating

material will uniformly flow through the apertures to provide a protective film for the metal covering all exposed surfaces.

It will, of course, be understood that various details of the invention may be varied through a wide range without departing from the principles of this invention and it is, therefore, not the purpose to limit the patent granted hereon otherwise than necessitated by the scope of the appended claims.

I claim as my invention:

1. Apparatus for removing sharp corners from apertured metal articles which comprises a pair of cooperating dies having leading ends with quarter-round peripheral grooves cooperating to provide a semi-cylindrical recess, and sleeves enveloping said dies having rounded leading ends for flowing metal into the recess.

2. Apparatus for removing sharp corners from apertured metal articles which comprises a pair of cooperating dies having leading ends with rounded peripheral grooves therearound adapted to cooperate to provide a rounded recess, and sleeves enveloping said dies having leading ends for acting on metal articles inserted between the dies to flow metal of the articles into the recess and provide apertures in the articles with smooth rounded defining walls.

BERNARD C. JOHNSON.
